(57) **CLAIM**

The ornamental design for an infrared oil heater, as shown and described.

DESCRIPTION

FIG. 1 is a front perspective view for an infrared oil heater showing the new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right-side view thereof; and,

FIG. 8 is an enlarged view of an end view cut through the 8-8 line of FIG. 4 thereof.

The broken lines are included for the purpose of illustrating unclaimed portions of the infrared oil heater and form no part of the claimed design.
